UNITED STATES PATENT OFFICE.

HERBERT F. COOK, OF CLEVELAND, OHIO.

TUBULAR BOILER.

SPECIFICATION forming part of Letters Patent No. 653,502, dated July 10, 1900.

Application filed September 13, 1899. Serial No. 730,336. (No model.)

To all whom it may concern:

Be it known that I, HERBERT F. COOK, a citizen of the United States, residing at Cleveland, in the county of Cuyahoga and State of 5 Ohio, have invented a certain new and useful Improvement in Tubular Boilers, of which the following is a full, clear, and exact description, reference being had to the accompanying drawings.

10 The object of the invention is to provide a boiler in which steam may be quickly and economically made.

To that end the invention consists in the construction and combination of parts shown 15 in the drawings and hereinafter described whereby extensive heating-surfaces are presented to the action of the heat and the water is allowed to circulate very freely through the parts whose surfaces are thus exposed to 20 the action of the heat, all of which will be definitely pointed out in the claims.

In the drawings, Figure 1 is a front view of the boiler with parts of the protecting front plate removed. Fig. 2 is a side view when 25 the side of the brick casing is removed. Fig. 3 is an end view, partly in section, of two of the headers of which the boiler ends are composed. Fig. 4 is a side view of one of said headers; and Fig. 5 is a transverse sectional 30 view on line 5 5 of Fig. 2, showing one of the deflecting-plates.

Each end of the boiler is made up of a group of vertical hollow headers A A', which are set side by side or nested, substantially 35 as shown. Each header has in its inner face the tube-holes a a', which are arranged in two vertical rows, substantially as shown, the holes in one row being staggered with respect to those in the other row. All of the 40 holes in one vertical row have a downward inclination, while those in the other row have an upward inclination. These holes a and a' respectively receive the ends of the tubes B and B', which ends inside the headers are 45 set in the usual manner. The tubes B in one vertical row are inclined from the horizontal in one direction while the tubes in the adjacent vertical row are inclined in the opposite direction. The outer walls of the headers have holes

a² in line with those in their inner walls, which 50 holes are closed in a suitable manner, as by the header-plates a³, held by crabs a⁵ and nutted bolts a⁶. The tube-holes a a' in the headers are so placed that the tubes in the two vertical rows will substantially touch 55 when they pass one another. (See Fig. 5.) In order that this condition may exist with respect to the adjacent tubes attached to different headers, the headers are made of the sinuous form shown; but the adjacent sides 60 of adjacent headers are of complementary form, whereby they nest together, as shown, and fit tightly against one another. Each header is connected at both its upper and lower ends with the two headers which lie at its 65 sides, these connections being made by the tubes C, which fit in holes a⁴ in the side of the headers and have their inner ends upset, as shown. Each header is connected by a tube D with the water-dome E, which dome 70 is substantially horizontal and is supported on the sides of the inclosing casing F in a position at right angles to the tubes. The tubes D all incline upward from the header to the dome. The outside headers in both 75 the front and back group have a lateral extension G G' at their lower and upper ends, respectively, and these extensions are connected, as shown, by the four vertical pipes H. At each end of the dome E, which overhangs 80 the brickwork, is a downwardly-extended pipe J, outside the brickwork, which is connected with a horizontal pipe K, and this horizontal pipe is connected at the ends with the lateral extensions G at the lower ends of 85 the outside headers.

The steam-dome N is supported above the water-dome and is in open communication therewith.

It is a well-known fact that steam does not 90 form from vertical heating-surfaces, and in my construction it will be observed that the pipes J are vertical. This is evidently a great advantage, as the steam which necessarily forms in inclined pipes impedes the downward flow of the circulating water. Now, as the pipes J are vertical and they, with the pipes communicating with their lower ends,

are removed from the heat of the fire, the circulation of the water must be greatly facilitated. In operation the steam forming in the heating-pipes flows directly to either header 5 and is immediately replaced by water rising through the opposite header. The rising water in the headers is supplied by the horizontal pipes K, which in turn receive their water from the vertical pipes J. Evidently the circulation in a boiler constructed so that the vertical pipes and their communicating pipes were within the brick housing and under the influence of the fire would still possess many advantages over ordinary boiler types. Hence 10 I do not confine myself to any particular location of the vertical pipes J nor to any particular form of boiler.

The inclosing shell F for the boiler, as described, may be built up from bricks, as shown, 20 or may be made of any other suitable material. Beneath one end of the tubes B B', within the shell, is the grate M, and above the other end of said tubes is the stack P. To cause such circulation of the heat as will 25 render it most effective, the space within the shell is divided by vertical partitions R and T, which are made up of independent plates r and t. These plates have notches r' and t' in their upper and lower edges, nearly semi- 30 circular in form, and when the plates are turned up into vertical position they lie in the vertical plane in which the oppositely-inclined tubes pass one another, and they engage with said tubes and substantially fill the 35 space between the tubes above and below them. The partition R nearest the grate, made up of the plates r, rests upon the arch f behind the grate, and there is a space between the top of the shell and said partition. 40 The other partition T extends from the top of the shell downward. The heat must therefore pass from the grate over partition R and under partition T and then up to the stack. The boiler is inclosed at each end by the pairs 45 of hinged doors L and L'.

Having described my invention, I claim—

1. In a tubular boiler, the combination of two groups of vertical hollow headers set side by side to form the ends of the boiler, each 50 header being connected at both its upper and lower ends with the header on each side of it, a plurality of substantially-vertical rows of inclined tubes which extend between the headers at one end of the boiler and those at 55 the other end, and are connected with said headers, the tubes in each vertical row being oppositely inclined to those in the adjacent vertical row, a water-dome, and pipes connecting it with the upper ends of the headers at both ends of the boiler, and pipes connecting 60 said dome with the lower ends of some of the headers at both ends of the boiler, substantially as specified.

2. In a tubular boiler, the combination of 65 the group of headers A A' which are connected at both their upper and lower ends and

constitute one end of the boiler, the group of headers A' which are similarly connected and constitute the other end of the boiler and the tubes B B' which extend from one group of 70 headers to the other and are connected with them, said tubes being arranged in vertical rows, of which the tubes in each row are inclined in opposite directions to the tubes in adjacent rows, with the water-dome, pipes 75 connecting it with the headers at both ends of the boiler, pipes connecting said dome with the lower ends of the outside headers in each group, and the vertical pipes at the four corners of the boiler, and connected with the 80 upper and lower ends of the four outside headers, substantially as specified.

3. In a tubular boiler, the combination of two hollow ends of the boiler, and tubes extending between and connected with said 85 ends, and arranged in substantially-vertical rows, the tubes in one row being inclined oppositely to those in adjacent rows, a water-dome, pipes connecting it with the upper parts of both of the boiler ends, and return- 90 pipes connecting it with the lower parts of said boiler ends, substantially as specified.

4. In a tubular boiler, the combination of a steam-dome, a water-dome communicating therewith, headers communicating with said 95 water-dome, inclined heating-tubes carried between the headers, and vertical circulating-pipes leading from the water-dome and communicating with the lower ends of the headers, substantially as specified. 100

5. In a tubular boiler, the combination of a steam-dome, a water-dome, inclined pipes connecting the water-dome with the upper ends of vertical headers, each header carrying two vertical rows of oppositely-inclined 105 heating-tubes, said headers communicating top and bottom with each other, and located close together to form solid walls, vertical circulating-pipes leading from the water-dome and communicating through horizontal 110 pipes with the lower ends of the headers, substantially as specified.

6. In a tubular boiler, the combination of two groups of vertical hollow headers set side by side, the headers of each group being successively connected and communicating at both ends, and having closed openings at 115 their backs, a plurality of substantially-vertical rows of inclined tubes which extend between the two groups of headers, and communicate therewith, the tubes in each vertical row being oppositely inclined to those in its adjacent rows, a steam-dome, a water-dome connected therewith, inclined pipes connecting said water-dome with the upper ends 120 of the headers, vertical circulating-pipes leading from the water-dome, and horizontal pipes connecting them with the lower ends of the headers, substantially as specified.

7. In a boiler, the combination of a steam- 125 dome, a water-dome communicating therewith, a set of heating-pipes, pipes leading

from the upper part of said set to said water-dome, a furnace-casing inclosing the heating-pipes, and circulating-pipes leading downward from the water-dome outside of said

5 casing and communicating to the lower part of said set of heating-pipes, substantially as specified.

In testimony whereof I hereunto affix my signature in the presence of two witnesses.

HERBERT F. COOK.
